Walter H. Underwood, Inventor

UNITED STATES PATENT OFFICE.

WALTER H. UNDERWOOD, OF NEW YORK, N. Y.

FASTENING DEVICE.

1,190,344.

Specification of Letters Patent.

Patented July 11, 1916.

Application filed June 16, 1909. Serial No. 502,512.

To all whom it may concern:

Be it known that I, WALTER H. UNDERWOOD, a citizen of the United States and resident of the borough of Manhattan, city, 5 county, and State of New York, have invented certain new and useful Improvements in Fastening Devices, of which the following is a specification accompanied by drawings.

10 This invention relates to a new device whereby two edges of material, either rigid or flexible may be drawn together and fastened firmly, readily and quickly, and opened or separated with equal facility. It 15 may be applied to shoes, leggings, all kinds of sacks, bags or pouches, placket holes in skirts, corsets and other articles which open and close where a movable flexible or collapsible fastener is useful.

20 To this end the invention consists of holding slides or slideways attached at or near the edges to be fastened together, prehensile eyelets or split rings, hereinafter described as sliders, adapted to slide to and fro on said slides, and laces, tongues or bars 25 connecting the eyelets or rings on one slideway with those on the other and formed and constructed as fully described and 30 claimed in this specification and illustrated in the accompanying drawing, in which:—

Figure 1 is a perspective view of the upper end and mouth of a sack or pouch fitted with a fastening device embodying my invention. Fig. 2 shows a fastening tongue 35 provided with suitable sliders or split rings. Fig. 3 is a cross section of the pouch opening shown in Fig. 1 with the tongue of Fig. 2 in position and closing the mouth of the pouch; Fig. 4 shows a portion of a tongue 40 provided with a modified form of slider. Fig. 5 shows the construction of a slideway embodying my invention. Fig. 6 shows the section of a body such as a shoe, legging, dress or similar article provided with an 45 opening fitted with a fastening device embodying my invention; and Fig. 7 shows a modified form of slideway embodying my invention.

50 In this invention the application of the device to a pouch is shown in Fig. 1 and to a shoe, legging, dress or the like is shown in Fig. 6. The slides or slideways are fastened securely longitudinally of the edges of the aperture to be closed. These slide- 55 ways may be made variously of different materials and of different form as may be

most adapted for the special use in each case. In Figs. 5 and 7 I have shown slideways consisting of wire bent or coiled into shape either cylindrical or otherwise, the 60 shape being immaterial so long as the slideway allows the slider to move freely to and fro on it while the slider is held firmly in place. The slideways *b* shown in Figs. 5 and 7 are provided with extension loops or eyes 65 *h* which may be formed integral with the same wire in the course of winding it. The loops *h* are adapted to extend through holes similarly spaced along the edges of the opening as shown in Figs. 1 and 3. In Fig. 70 7 the slideway *b* is reinforced by inserting a coiled spring within it. The inner ends of the loops *h* are held in place by a continuous check cord *i* which is separate from the loops and extends through all of them to 75 secure the continuous slideways *b* to the outer side of the body along the edges of the opening therein.

The closing tongue *g* shown in Figs. 2, 3, 4 and 6 consists of a single piece of flexible 80 material such as leather or of the material of which the body of the device having the opening therein is made. The tongue *g* is suitably fitted with the sliders or prehensile metal split rings *c* which are bent so as 85 to fit around the slideway *b* as shown in Figs. 2 and 3 so that they will resiliently grasp the slideways and be capable of sliding along them. The sliders *c* in Fig. 4 are independently and firmly connected with 90 the bar *g'* for greater strength and to allow the tongue *g* to be removed in whole or part for any purpose without opening the aperture. The sliders are fastened to the tongue by rivets or in any other suitable manner 95 and the aperture is opened or closed by sliding them to and fro on the slideways *b*.

In applying this construction to a shoe it is desirable to place the slideways on the quarters back from the edge of the top so 100 that the ends will be somewhat farther apart at the top than at the bottom, giving the tongue the shape of an elongated V, as shown in Fig. 6 and thus providing ample opening when the tongue is pushed down to 105 put on or take off the shoe without difficulty. This construction is also well adapted for strength and rough usage such as in mail pouches or sacks and the like. In a pouch the slides at one end may extend down the 110 sides of the pouch as shown in Fig. 1 to allow space for the tongue and sliders to rest

when pushed back from the opening. To hold the tongue in place when the pouch is closed a slit may be made at the end which is to be fitted over a staple or similar convenient fastener and a padlock applied in the usual manner. In the reinforced wire slide shown in Fig. 7 the second coiled wire may be inserted within the slideway *b* and coiled in the reverse direction to make the same more rigid.

While I have shown and described the invention in detail I do not wish to be limited to the exact embodiment illustrated as it is obvious that various minor changes may be made without departing from the spirit of the invention.

I claim and desire to obtain by Letters Patent the following:

1. A fastening device consisting of flexible slideways composed of coiled wire provided with loops of the same wire formed tangent to the coils, said loops constituting means whereby said slideways may be secured to a support, prehensile members fitted to said slideways and adapted to move to and fro thereon, and a means adapted to connect the prehensile members on one slideway with the prehensile members on the other slideway, substantially as and for the purpose set forth.

2. A fastening device comprising flexible slideways composed of wires in the form of continuous coils and provided with integral loops formed tangent to the coils, a cord or the like adapted to pass through said loops and secure the same to a support adjacent the aperture therein, said loops being adapted to pass through the support adjacent the aperture therein to receive said cord or the like, prehensile members fitted to said slideways and adapted to move longitudinally

thereon, devices, each having the members associated with one slideway secured thereto, and means for connecting said devices together.

45

3. A device for closing an aperture in a flexible body comprising flexible slideways consisting of continuous coils of wire provided at intervals with integral loops, said loops being adapted to extend through said body adjacent the aperture therein, a flexible member adapted to pass through said loops on the opposite side of said body from the slideways thereon and adapted to secure said slideways to said body adjacent the aperture therein, and means fitted to said slideways whereby the edges of the apertures may be drawn together to close the aperture.

50

4. A device for fastening together the edges of a flexible body, said device comprising slideways extending longitudinally of the edges to be fastened together, each slideway comprising a single length of wire spirally wound and provided at intervals with integral parts extending through said body to the opposite side thereof, members separate from said parts and coöperating therewith to secure said slideways in place, one of said members being associated with each slideway and extending parallel thereto on the opposite side of said body therefrom, and means fitted to said slideways whereby said edges may be drawn together.

55

In testimony whereof I have signed this specification in the presence of two subscribing witnesses.
